UNITED STATES PATENT OFFICE.

CHARLES E. HOPKINS, OF PLAINFIELD, NEW JERSEY; THE PLAINFIELD TRUST COMPANY ADMINISTRATOR OF SAID CHARLES E. HOPKINS, DECEASED.

CONTROLLING MECHANISM.

Original application filed February 25, 1911, Serial No. 610,834. Divided and this application filed July 12, 1920. Serial No. 395,559.

To all whom it may concern:

Be it known that I, CHARLES E. HOPKINS, a citizen of the United States, residing at Plainfield, in the county of Union and State 5 of New Jersey, have invented a new and useful Controlling Mechanism, of which the following is a specification.

This is a division of my Patent No. 1,286,- 323, on a machine for making stereotype 10 plates, patented Dec. 3, 1918, on an application filed February 25, 1911, Serial No. 610,- 834 and its divisional application Ser. No. 159,117 filed April 2, 1917.

The invention comprises a practicable 15 simple and convenient mechanism for controlling the operations of an automatic machine. I have illustrated it as employed for controlling the parts of a machine for finishing and cooling stereotype printing 20 plates. Such a machine is designed for shaving the ribs cast on the concave surface of the plate, cutting off the riser, beveling the riser and, gradually lowering and finally dropping the tail cut off, releasing the plate 25 and allowing it to be fed by gravity from the finishing mechanism to a final cooling mechanism.

More specifically it involves connections 30 whereby the operator can start the machine by pushing on a pedal or lever and can stop it again at any point in its cycle of motion by operating the same pedal or lever in the same direction and in the same way.

The invention also involves numerous improvements in details of construction and in 35 mechanism for carrying out the objects elsewhere specified herein.

Reference is to be had to the accompanying drawings in which.

Fig. 1 is a side elevation of a part of a stereotype finishing machine constructed in accordance with this invention, and

Fig. 2 is a transverse sectional view on the line 2—2 of Fig. 1.

In order to get a general idea of the invention it may be stated that the drawing shows a machine embodying a stereotype plate finishing mechanism which delivers to a cooling device a cast and finished stereotype printing plate.

I will not explain the mechanism for shaving the ribs cast on the concave surface of the stereotype plate, the mechanism for cutting off the riser and beveling that curved

end, or the means for conveying the finished stereotype plate from the finishing mechanism to the cooling mechanism.

Mounted on the frame is a longitudinal main shaft 158 operated as will be explained hereinafter. Fastened to the main shaft is 60 a shaving knife which extends lengthwise, the said knife being so positioned as to engage and smooth off the faces of the ribs cast on the stereotype concavity.

The main shaft is caused to make one revolution each time a foot trip or pedal 59 is pushed down and released to operate a clutch jaw 33. During the revolution of the main shaft a stereotype plate is shaved and the riser cut free from the said plate, by tools 70 carried by the said shaft, which engage the stereotype plate.

It must be understood that a cross shaft 31 is revolved continuously by the driving shaft 52 to which it is connected by beveled gears 55. The driving shaft is driven by any suitable source of power and connection a belt and pulley 54 on the shaft 52, being shown for this purpose.

The construction and operation of the 80 shaving and trimming mechanism is fully shown and described in my above mentioned Patent No. 1,286,323. I will only show and describe the mechanism shown for operating the same.

Keyed to the lower end of what I call the main shaft 158, that is, the main shaft of the finishing device, is a hub 27. Rotatably mounted on the hub is a large worm gear 25 which for the purpose of preventing accident is made in two parts, one of which is a toothed rim 26 with a flat web. The hub 27 has a broad flange 28 which contacts with the said web. The rim and hub are made to travel together by a breaking pin 95 29 positioned in a hole through both members. The reason for making the gear in two parts is to prevent accident in case the main shaft should for any reason be prevented from moving with the gear in which case as constructed the pin 29 would be cut in two and no other damage done.

Positioned below the worm gear and loosely mounted on a cross shaft 31, so as to mesh with the gear teeth is a worm 32. One 105 end of it is formed with a clutch jaw 33. Mounted on the same shaft and facing the jaw 33 of the worm is a sliding jaw 34.

which is made to revolve with the shaft. Pivoted below this jaw on a stud 35 fastened in a leg of the frame is a shifting yoke 36 carrying projections 37 which engage in a 5 groove 38 made around the sliding jaw member. One of the arms of the yoke extends upward and mounted on a stud 39 in said extension is a small roller 40. To the face of the worm gear 25 is pivoted a latch 42 positioned so that after each revolution of 10 the worm gear it will engage the roller 40 and force the jaws of the sliding clutch out of engagement with the jaws of the worm, and hold them disengaged until the latch 15 is moved on its pivot out of engagement with the yoke extension roller 40. The yoke at all times is held toward the engaging position by a compressed spring mounted on a rod 44 operating through a bracket 45 20 on the frame, the rod being attached to the yoke extension 36.

A trip mechanism for disengaging the latch 42 is located so as to push the said latch up and free from the yoke extension roller. This consists of an upright rod 48, operating in bearings on a leg of the frame and carrying on its top an extension 49 with, a beveled side 47. This extension when pushed up a short way, engages with 25 a pin 50 on the side of the latch which raises said latch and thus releases the yoke 36. Then the spring on the rod 44 turns the yoke which in turn advances the sliding jaw into engagement with the jaw on the 30 worm.

The means employed for operating the trip rod 48 consists of a short lever 56, fast 35 on a rod 57, operating in bearings and extending lengthwise of the machine and located at the back side but beneath the frame. To the opposite end of this rod is fastened an arm 58 which extends toward the front side of the machine. To a convenient frame is pivoted on a stud a foot pedal 59 40 having an extending arm which engages the arm 58.

By this mechanism the operator, by pushing the pedal down, can force the latch 42 out of engagement with the yoke extension 45 and thereby start the machine. It will continue until the latch acts to stop it. But in case he wishes to stop the machine for any reason before the latch acts, a second push downward will force the beveled 55 edge 47 of the extension of the cam 49 up into engagement with the yoke extension roller 40 and force the jaws of the clutch out of engagement. A spring 60 is mounted on the upright rod for the purpose of holding 60 the said rod down and out of the path of the latch when the machine is in operation, and returning the pedal to its normal raised position.

I do not claim herein the combination of 65 this mechanism with the finishing machine

as that is included in my above mentioned application Serial No. 159,117.

Although I have illustrated and described a preferred embodiment of the invention and shown it as applied to a specific machine, I am aware that many modifications can be made therein and that its principles can be applied to other machines by any person skilled in the art without departing 70 from the scope of the invention as defined 75 in the appended claims.

Therefore I do not wish to be limited to all the details of construction herein shown and described, but what I claim is:—

1. The combination with a driving shaft 80 and a finishing shaft, of a clutch for connecting said shafts, a member rotatable with the finishing shaft, a shifting yoke for operating said clutch, a latch movably mounted on said rotary member in such 85 position that after each revolution thereof it will engage and operate the shifting yoke to disengage the clutch and hold it disengaged, and means for moving the latch on the rotary member to inoperative position. 90

2. The combination with a driving shaft and a finishing shaft, of a clutch for connecting said shafts, a shifting yoke for operating said clutch, a latch in such position that it will periodically operate the shifting yoke to force the clutch out of engagement and hold it disengaged until the latch is moved out of engagement with the yoke, resilient means for holding the 100 yoke normally in its engaging position, a rod, and a pin on the latch in position to be engaged by said rod, whereby the latch will be moved out of engagement with the yoke. 105

3. The combination with a driving shaft and a second shaft, of a clutch for connecting said shafts, a yoke extension for operating said clutch, a latch for controlling said yoke extension, a lever or pedal located in position for forcing the latch out of engagement with the yoke extension, a spring for connecting the clutch and starting the second shaft when the pedal or lever is pushed down, and means whereby 115 when the pedal or lever is pressed downward again the clutch will be disengaged. 116

4. The combination with a driving shaft and a second shaft, of a clutch for connecting said shafts, a lever or pedal, yielding 120 means controlled thereby for connecting the clutch and starting the second shaft when the lever is pushed, and positive means whereby when the pedal or lever is pressed again in the same direction the shafts will 125 be disconnected.

5. The combination with a driving shaft and a second shaft, of a clutch having jaws for connecting said shafts, a member rotatable with the second shaft, a pivoted 130

shifting yoke for operating said clutch, a pivoted latch on said rotary member in a position to engage and operate the shifting yoke at each rotation of the rotatable member to force the jaws of the clutch out of engagement with each other and hold them disengaged until the latch is moved out of engagement with the yoke, and resilient means for holding the yoke normally in its engaging position.

6. The combination with a driving shaft and a second shaft, of a clutch, having jaws for connecting said shafts, a member rotatable with the second shaft, a shifting yoke for operating said clutch, a latch on the rotatable member in a position to engage and operate the shifting yoke at each rotation of the rotatable member to force the jaws of the clutch out of engagement with each other, resilient means for holding the yoke normally in its engaging position, and a trip mechanism for disengaging the latch.

7. The combination with a driving and a driven shaft, and a clutch for connecting said shafts, of a wheel on the driven shaft, a yoke for operating said clutch, a latch movably mounted on said wheel in position to engage and operate the yoke to separate the members of the clutch and disconnect the driven shaft from the driving shaft, a starting pedal, means connected with said pedal for moving said latch to inoperative position, and constantly operating yielding means for then acting on the yoke to restore the clutch to operative position and connect the two shafts.

8. The combination with a driving and a driven shaft, and a clutch for connecting said shafts, of a wheel on the driven shaft, a yoke for operating said clutch, a latch movably mounted on said wheel in position to engage and operate the yoke to separate the members of the clutch and disconnect the driven shaft from the driving shaft, a starting pedal, means connected with said pedal for moving said latch to inoperative position, and constantly operating yielding means for then acting on the yoke to restore the clutch to operative position and connect the two shafts, said means operated by the pedal also having means for disengaging the clutch members if the pedal is depressed a second time while the driven shaft is rotating.

9. The combination with a driving and a driven shaft, and a clutch for connecting

said shafts, of a wheel on the driven shaft, a yoke for operating said clutch, a latch movably mounted on said wheel in position to engage and operate the yoke to separate the members of the clutch and disconnect the driven shaft from the driving shaft, a starting pedal, means connected with said pedal for moving said latch to inoperative position, and constantly operating yielding means for then acting on the yoke to restore the clutch to operative position and connect the two shafts, said latch being in position to again operate the yoke when the driven shaft has made a complete revolution and thus automatically stop the driven shaft at that time.

10. The combination with a driving shaft and a finishing shaft, of a clutch for connecting said shafts, a member rotatable with the finishing shaft, a shifting yoke for operating said clutch, a latch movably mounted on said rotary member in such position that after each revolution thereof it will engage and operate the shifting yoke to disengage the clutch and hold it disengaged, and means for moving the latch on the rotary member to inoperative position, said means comprising a sliding rod having a head for operating the latch, a spring for holding the rod in inoperative position, and a starting pedal having connections for moving the rod against the action of the spring into a position for moving the latch.

11. The combination with a driving shaft and a finishing shaft, of a clutch for connecting said shafts, a member rotatable with the finishing shaft, a shifting yoke for operating said clutch, a latch movably mounted on said rotary member in such position that after each revolution thereof it will engage and operate the shifting yoke to disengage the clutch and hold it disengaged, and means for moving the latch on the rotary member to inoperative position, said means comprising a sliding rod having a head for operating the latch, a spring for holding the rod in inoperative position, a starting pedal having connections for moving the rod against the action of the spring into a position for moving the latch, said head also having a beveled side adapted to engage the yoke after the machine is started and move the yoke to a position to disengage the clutch sections.

In testimony whereof I have hereunto affixed my signature.

CHARLES E. HOPKINS.
